DAVID C. HEDLUND, OF SPOKANE, WASHINGTON.

COMBINATION-TOOL.

1,250,455.

Specification of Letters Patent. Patented Dec. 18, 1917.

Application filed January 8, 1917. Serial No. 142,321.

To all whom it may concern:

Be it known that I, DAVID C. HEDLUND, a citizen of the United States, residing at Spokane, in the county of Spokane, State 5 of Washington, have invented new and useful Improvements in Combination-Tools, of which the following is a specification.

This invention relates to improvements in combination tools and has to do more particularly with that class of tool which is employed in fastening a wrapping wire about a bundle of wood, such as a bundle of box sides or bottoms, and then cutting the wire.

The invention has to do more particularly 15 with what is commonly known as a hand tool, in contra-distinction to that class of tools which are mounted upon a fixed support.

In the most improved embodiment of my 20 invention, the same involves pivotally united levers having handle ends on one side of their pivotal juncture, there being a wire gripping device and a wire severing device on the opposite side of the pivotal juncture. 25 One of the special novelties consists in mounting one element of the wire gripping device upon one lever, the other element of the gripping device being operatively connected with the remaining lever, on that side. 30 of the pivotal juncture, opposite, the side on which the severing device is mounted, or in other words, on that side of the pivotal juncture which I will term the handle end side. With this construction, the coacting 35 members or elements of the wire gripping device are both actuated, simultaneously, toward a gripping position, when the handle ends of the levers are actuated or contracted. By means of this construction, the gripping 40 device can be closed from a wide open position with a very slight movement or slight degree of actuation of the handle ends.

Coacting cutting edges forming the severing device are mounted upon the levers, one 45 upon each lever, and this severing device is disposed in such close relation to the gripping device that the wire may be cut at the same time that it is gripped, and with the same operation of the levers, so that in one 50 operation of the hand levers the operator will grip and cut the wire preparatory to twisting or turning the tool to impart a twist to the wrapping wire such as will hold

the same tightly around the bundle. This operation also facilitates severance of the 55 wire with the least possible loss or waste.

The interdependence between the gripping device and the cutting device resides in the novel manner in which the elements of these two devices are mounted upon the 60 hand levers so that operation of the levers simultaneously operates both the gripping device and the severing device.

Other features and objects of the invention will be more fully described in connection with the accompanying drawing, and will be more particularly pointed out in and by the appended claim.

In the drawing:

Figure 1 is a view in side elevation showing the device in an open position ready to grip the wires and also sever the same.

Fig. 2 is a similar view showing the device closed for gripping and severing the wires.

Fig. 3 is a sectional view on line 3—3 of Fig. 2.

Fig. 4 is a plan view of the tool in the position shown in Fig. 2.

Like characters of reference designate similar parts throughout the different figures of the drawing.

As illustrated, my invention includes two levers which are disposed in crossed relation and which are pivotally united by a pivot bolt 1, one lever having a handle end 2 and the other lever having a handle 3, the handle ends being on the left hand side of the pivot 1, as shown. The handle end 2 has a leverage extension 4 which projects laterally or to one side of the pivot 1 for a considerable length, in order to form an operative portion which will be presently described. An expansively acting spring 5 is interposed between the handle ends 2 and 3 to normally separate the latter and the spring is shown mounted at its ends about retaining lugs 6 and 7 which may be cast integral with the handle ends 2 and 3.

On the right hand side of the pivotal juncture 1 the handle end lever 2 is provided with an extension 8 to which is mounted one member 9 of a severing device. The member 9 is provided with a cutting edge 10 and is suitably shouldered, as indicated at 11, so as to fit about two sides of the extension 8 and be suitably secured thereto by

means such as screws 12. This construction provides for removal of the cutting edge member 9 for sharpening purposes or for renewal, when necessary.

5 On the opposite side of the pivot 1, from the handle end side, is a supporting extension 12 on which is mounted the companion cutting edge member 13, of the severing device. Said member 13 is provided with a 10 cutting edge 14, coacting with the cutting edge 10, said cutting member 13 being secured to the supporting extension 12 by means such as rivets or bolts 15. Thus it will be seen that one member of the cutting 15 device is mounted upon one operative extension of one lever, while the other member is mounted on an operative extension of the other lever. When the handle ends 2 and 3 are contracted, from the position shown in 20 Fig. 1 to the position shown in Fig. 2, the cutting or severing members will be correspondingly moved to sever the wire.

I will next describe my novel gripping device and the manner in which the same operates.

25 The operative end or extension 12 is provided with a bearing 16 which is shown to be of cylindrical form and which is also illustrated as having a cylindrical bore 17. 30 It will be noted that the bearing 16 is in very close juxtaposition to the severing device, a point of advantage which will be presently developed in the following description. The end 18 of the bearing member 35 16, forms an operative part of the gripping device, the end 18 coacting with a companion gripping member which I will now describe in detail. The companion gripping member comprises a shank 19 which is 40 of cylindrical cross-section so as to accurately fit and reciprocate in the bearing 16. On the operative end of the shank 19 is formed a hook 20 which is proportioned so as to contract into and within the bearing 45 16, as illustrated in Fig. 2.

I will next describe an important feature 50 of the invention which consists in the operative connection of the shank 19 with the end lever 2 at a point on the opposite side of the pivotal juncture 1 with respect to that side upon which the severing and gripping devices are located and operated.

In the particular form shown, the leverage extension 4 is bifurcated to form pivot jaws 55 21. A pivot 22 is suitably fixed in said jaws. The shank 19 is reduced, as indicated at 23, to fit between said jaws, and the reduced portion 23 is slotted at 24. On the pivot 22 is mounted an anti-friction roller 25 which 60 closely fits the slot 24. The slot 24 is of sufficient length to permit of relative movement of the roller 25 and the pivot 22 in the slot 24 which is made necessary by reason of the fact that the shank 19 moves linearly in the bearing 16 whereas the pivot 22

moves about the pivotal juncture 1, as a center. By connecting, operatively, the shank 19 with the lever 2, on the lever end side of the pivot 1, I am able to close the gripping device against the wire and also close the nippers, by one contractive movement of the lever ends 2 and 3.

In operation, it is possible, after wrapping the wire around the bundle to dispose the excess lengths in the gripping device, in the 75 manner as shown in Fig. 1. That length of the wire extending from the gripping device, may be disposed between the severing members 9 and 13, as shown in Fig. 1. Thus in one operation of the lever ends 2 and 3, contracting the same from the position shown in Fig. 1 to the position shown in Fig. 2, it is not only possible to sever the excess wire but also grip the same so that the operator, after completing this operation, will be free to bodily rotate the tool about its longitudinal axis in order to twist the gripped ends of the wire in such a manner as to tighten and secure the wire about the bundle in firm manner. Wire of sufficient strength is used so that it is not necessary to actually knot the wire in order to securely tie the bundle. If it is not desired to simultaneously grip and sever the wire, the wire may be gripped and twisted in 95 order to tie the bundle and then after the bundle is tied, the remaining or excess length of the wire may be severed. However, saving of time is an important factor and where it is possible to save one complete operation, it is desirable so to do, providing that the waste of wire is not too great.

Now it is an important feature of this invention to dispose the severing device in such close relation to the gripping device 105 that the wire may be gripped and severed in one contracting operation of the handle ends without a too great waste of wire. It will be understood that in twisting the ends of a tying wire it is necessary to have some 110 little excess length in order to form the twist. Now therefore I place the severing device sufficiently close to the gripping device to provide for this excess length and practically no more.

115 It will be seen that the extension 12, not only supports the severing member 13, but the bearing 16, which is one member of the gripping device. Now the interdependence between the severing device and the gripping device, patentably speaking, resides in such a disposition of these two devices with their separate pairs of coacting members disposed in such a manner that both of these devices will be moved into an operative position by contraction of the handle lever ends 2 and 3. This is effected by having the severing devices mounted upon the levers, on one side of the pivotal juncture, and connecting the remaining member of 120 125 130

the gripping device, operatively with one of said levers on the opposite side of the pivotal juncture of the latter.

It is believed that the novelty and utility 5 of my invention will be clearly understood from the foregoing description and while I have herein shown and described one specific form of my invention, I do not wish to be limited thereto except for such limitations as the claim may import.

I claim:—

A wire twisting and cutting hand tool comprising in combination, pivotally united crossed nipper and bearing levers having 15 handle ends on one side of their pivotal juncture and the nipper lever and bearing lever each having cutting edges on the re-

maining side of their pivotal juncture coacting to form nippers, said bearing lever having a twister bearing on the nipper side of the 20 pivotal juncture, a wire hook reciprocable in said bearing and co-acting with said bearing to form a wire gripper, and means connecting said hook and said nipper lever on the handle side of said pivotal juncture 25 whereby movement of the handle ends toward each other will simultaneously move both the bearing and hook into a gripping position and close said cutting or nipper edges, substantially as described.

In testimony that I claim the foregoing as my own, I hereby affix my signature.

DAVID C. HEDLUND.
